CLAIM

The ornamental design for faucet, as shown and described.

DESCRIPTION

FIG. 1 is a right side view of faucet showing my new design.

FIG. 2 is a front view of faucet showing my new design; and, FIG. 3 is a top view of faucet showing my new design.

The broken lines showing of hoses, mounting surfaces and handle are for illustrative purposes only and forms no part of the claimed design.

1 Claim, 1 Drawing Sheet

FIG. 1

FIG. 2

FIG. 3
